DESIGN FOR A CHEST FOR SILVERWARE
OR THE LIKE

Albert E. Sloan, Chicago, Ill.

Application March 22, 1946, Serial No. 127,780

Term of patent 3½ years

(Cl. D58—11)

To all whom it may concern:

Be it known that I, Albert E. Sloan, a citizen of the United States, residing at Chicago, in the county of Cook and State of Illinois, have invented a new, original, and ornamental Design for a Chest for Silverware or the like, of which the following is a specification, reference being had to the accompanying drawing, forming a part thereof.

In the drawing:

Fig. 1 is a plan view of a chest for silverware or the like, embodying my new design;

Fig. 2 is a side elevation of the same; and

Fig. 3 is an end elevation of the same.

I claim:

The ornamental design for a chest for silverware or the like, as shown.

ALBERT E. SLOAN.
